MECHANISM FOR EJECTING SHUTTLES IN LOOMS

Woodruff T. Sullivan, Norwich, Conn.

Application June 8, 1954, Serial No. 435,217

1 Claim. (Cl. 139—134)

This invention relates to looms, and has special reference to the means for propelling loom shuttles across the lay.

More particularly the invention relates to a structure for this purpose, utilizing two shuttles simultaneously reciprocable on the lay from one shuttle box to the other.

One important object of the invention is to provide novel means for propelling or actuating shuttles across the lay from one box to the other.

A second important object of the invention is to provide a loom of this description having a lay equipped at each end with a shuttle box adapted to hold two shuttles, the loom having means to simultaneously propel or actuate a pair of shuttles from one double shuttle box to the other.

A third important object of the invention is to provide means to equalize the propulsive movement of each shuttle of such a pair.

A fourth important object of the invention is to provide electrical means for actuating such a pair of shuttles.

A fifth important object of the invention is to provide means for actuating the shuttles electrically and including circuits and lay operating shaft wherein the operating circuits for the shuttles are controlled in synchronous relation with the action of the lay.

A sixth important object of the invention is to provide a mechanism for greatly increasing the efficiency of the type of loom used in weaving such fabrics as velvets.

A seventh important object of the invention is to provide a greatly simplified construction from that heretofore used for accomplishing the purposes desired.

With the above and other objects in view, the invention consists in general of certain novel details of construction and combinations of parts hereinafter fully described, illustrated in the accompanying drawings, and particularly claimed.

In the accompanying drawings, like characters of reference indicate like parts, and:

Fig. 1 is a fragmentary front elevation of a loom showing the improvements covered by the present invention.

Fig. 2 is an enlarged side elevation of a portion of one end of the loom lay, the shuttle boxes and the actuating means therefor.

Fig. 3 is a plan view of the parts shown in Fig. 2.

Fig. 4 is a section on an enlarged scale on the line 4—4 of Fig. 2.

Fig. 5 is a perspective view of one of the shuttle propelling units.

Fig. 6 is an enlarged side view of Fig. 5.

Fig. 7 is a diagrammatic view of the circuit connections and operating means for the circuit closers as used in this invention.

Fig. 8 is a detailed elevation of a portion of Fig. 1.

Fig. 9 is a section on the line 9—9 of Fig. 8.

Fig. 10 is a section on the line 10—10 of Fig. 8.

Fig. 11 is a detail view of the lay connection to the drive shaft.

2

In the invention as here disclosed, there is illustrated a portion of a loom having end frame members 10. Through these frame members 10 extends a suitable motor-driven operating shaft 11 arranged to oscillate arms 12 carrying a lay 13, this shaft being connected by gears 11a and 11b with a shaft 11c journaled in the frame members 10. At each end of this lay there is provided a pair of shuttle boxes 14 and 15 arranged in superimposed relation. At the outer end of each of these shuttle boxes there is provided a reciprocating reversing motor device such as is shown in the patent to P. Trombetta, No. 2,337,430 of December 21, 1943, this device being indicated in general at 16. The core 17 is in the form of a flat plate which extends edgewise between the two shuttle boxes and on each forward end of this plate there is mounted a shuttle actuating member having a body 18 as in Fig. 5, provided with a forked extension 19 receiving one forward corner of the core 17. Member 18 is provided with suitable bolt holes 20 in the arms of the fork and through these bolt holes and corresponding holes in the core 17 extend securing bolts 21. At their inner ends the members 18 are provided with conical sockets 22 for engagement with the inner ends of shuttles 23 when the latter are in position in the shuttle box, 25 Suitable restraining springs 24 are secured to a supporting member 16a and bear against leaves 25 which press inwardly against the shuttles 23 when the latter are received in the respective boxes, the leaves 25 acting as friction means to prevent bouncing of the shuttles after 30 reaching their terminal position.

As shown in Fig. 7 there is provided a three-wire electrical supply of which 28 may be considered as the positive winding, 29 as the negative winding and 30 as the neutral winding. At 31, 31a are shown actuating windings of the Trombetta device and the two windings 31 and 31a are connected to the supply line 28 in multiple by conductors 32. Similarly there are second actuating windings 33 and 33a of the Trombetta device and the windings 33 and 33a are connected in multiple through 35 conductors 34 and 34a to the feed line 29. The neutral or return line 30 is connected to the opposite ends of each Trombetta windings 31 and 31a and windings 33 and 33a as at 35 and 35a by means of branch conductors 36 and 36a.

At 37 is a main switch which is closed only to provide current from the supply lines. At 37a and 37b are circuit controlling devices for opening and closing circuits through lines 34 and 34a, Trombetta windings 33 and 33a, Trombetta windings 35 and 35a, and return lines 36 and 36a. At 38 and 38a are shown similar circuit closing devices controlling the circuits between the lines 36 and 36a, the lines 34 and 34a, Trombetta windings 33 and 33a, and the remainder as shown by the windings 35 and 35a.

In order to understand the operation of the device, reference will be had to Fig. 7, and it will be assumed that the shuttles are located in the right hand shuttle box. The shaft 11c carrying the cams 39 and 39a and 40 and 40a is revolving. During the revolution of this shaft, the cams 40 and 40a move to position to close the right hand circuit closer 37a. At this time the left hand circuit closer 37b and both circuit closers 38 and 38a are open. Upon the closing of the right hand circuit closer 37a, the core of the reversing motor device 16 is thrown to the left and this causes the shuttles to traverse the lay from right to left and to be received in the left hand shuttle box. As the shaft 11c continues to rotate, the right hand circuit closer 37a opens, and the right hand cam 39 closes the right hand reverse closer 38. At this time the left hand reverse closer 38a and both closers 37a and 37b are open. This causes the core of the motor device to retract. As the circuit stands at the beginning

of the operation, the left hand core 17 is in retracted position to allow for the setting of the shuttles when thrown from right to left. Upon the shuttles being received in the left hand shuttle box, the next step in the operation is effected by the rotative action of the left hand cam which closes the left hand circuit closer 37b and this causes the core of the reversing motor device 17 to move to the right and eject the shuttles to be thrown, to the right hand shuttle box. When the left hand circuit closer 37b is closed, the right hand circuit closer 37a is open and both of the circuit closers 38 and 38a are open. Continuation of the rotation of the shaft 11c next causes the left hand circuit closer 37b to open. Following this, the left hand cam 39a is rotated to close the left hand circuit closer 38a and this retracts the core 17 of the left hand motor device. The shuttles have now been shot from left to right ready for the next cycle of operations as just described.

It is obvious that minor changes may be made in the form and construction of this invention without departing from the material principles thereof. It is not therefore desired to confine the invention to the exact form herein shown and described, but it is wished to include all such as properly come within the scope claimed.

What is claimed is:

In a loom, an oscillatable lay, shuttle boxes at the opposite ends of said lay, shuttle propelling means comprising a controlled reversible motion adapted to actuate a core comprised of a flat plate extending edgewise be-

tween the shuttle boxes and provided at each forward end with a shuttle engaging means having means comprising a forked extension adapted to engage said core at either end, each one of said shuttle engaging means including at its other end a conical socket for the engagement of a shuttle, spring means adapted to preclude bouncing of the shuttle, electro-magnetic means adapted to energize said core and hence oscillate said shuttle between said boxes, conductive controlling circuits for actuating said electro-magnetic means, each circuit including a reciprocable core and energizable windings adapted to reciprocate said cores, said cores being connected to opposite shuttle boxes, the circuits each including a circuit closer, a rotatable shaft connected to the lay and effecting oscillation thereof, and a pair of circular members having abrupt cam surfaces in diametrically opposed relation mounted in closely adjacent position, on said shaft, said abrupt cam surfaces alternatively actuating said circuit closers in timed relation to the oscillatory movement of said lay.
